Patented Mar. 23, 1920.

UNITED STATES PATENT OFFICE.

HOWARD B. STAMM, OF CINCINNATI, OHIO.

SEARCHLIGHT.

1,334,471.

Specification of Letters Patent. Patented Mar. 23, 1920.

Application filed March 31, 1919. Serial No. 286,318.

To all whom it may concern:

Be it known that I, HOWARD B. STAMM, a citizen of the United States, residing at Cincinnati, in the county of Hamilton and State 5 of Ohio, have invented certain new and useful Improvements in Searchlights of which the following is a specification.

My invention relates to improvements in search lights for automobiles and similar 10 purposes. One of its objects is to provide an improved reflector adapted to direct the light rays in the desired direction and to avoid a blinding glare in the eyes of pedestrians or drivers of vehicles moving in the 15 opposite direction. Another object is to provide an improved reflector for the purpose readily applicable to search lights heretofore in use to incorporate therein the desirable reflecting properties mentioned. My 20 invention also comprises certain details of structure and arrangement, all of which will be fully set forth in the description of the accompanying drawings, in which:

Figure 1 is a front elevation of a search 25 light embodying my improvements.

Fig. 2 is a central vertical section on line 2 2 of Fig. 1.

Fig. 3 is a plan of my improved supplemental reflector detached.

30 Fig. 4 is an enlarged sectional detail.

Fig. 5 is a detail perspective view of a portion of the detachable reflector.

The accompanying drawings illustrate the preferred embodiment of my invention 35 in which 5 represents a parabolic reflector of the general type heretofore in use, 6 represents a plane glass or lense across the front of the reflector, and 7 a metal housing or casing of usual type. An incandescent electric 40 light bulb or other source of light 8 is located at the focus of the parabolic reflector 5 to afford a strong pencil of light-rays directed at the road some distance in advance of the vehicle, and requisite on count- 45 try roads and other places where the streets and roads are not otherwise illuminated.

A similar but smaller incandescent electric light bulb 9 is also preferably provided to provide a dimmed light for use as a signal light where the use of the bulb 8 would afford an unnecessary amount of light.

In order to direct the rays from the bulb 8 forward and downwardly upon the road, and so as to prevent rays therefrom entering the eyes of pedestrians on the street or

drivers of other vehicles, I provide a supplemental or insert reflector 10, which presents two convex faces upwardly toward the bulb 9 and two concave faces downwardly toward the bulb 8, and is provided with a 60 downwardly directed tongue 11 at its forward central portion in position to be interposed in front of and to intercept any rays which might issue directly from the bulb or source of light 8 so as to enter the eyes 65 of a pedestrian or other driver.

The two convex concave reflector sections 10' and 10'' are united at the vertical center in a downwardly projecting rib or crease 13. The reflector so arranged serves to diffuse 70 the light issuing from above the reflector 10, and to concentrate the light issuing from below reflector 10. The light issuing from below the reflector 10 is directed in a fan or blade shaped pencil slightly downwardly 75 and evenly over the face of the road, where it serves its purpose of enabling the operator to guide his machine without directing rays of light into the eyes of others. This form of supplemental or insert reflector with its 80 downwardly directed medial rib is relatively rigid and well adapted to retain its position relative to the light bulb and the parabolic reflector, and to conserve and concentrate the light upon and adjacent to the road where 85 it will best serve the operator's purpose without injury to others.

The insert reflector 10 has lugs 12 at opposite sides at the front, to be clamped between the glass 6 and the marginal face 90 or flange 14 of the parabolic reflector to hold the reflector 10 in position, and at the rear reflector 10 has a recess 19 which fits over and is supported by the tubular socket 20 of the light bulb to firmly support the reflector 95 10 in place. Reflector 10 preferably also has a marginal band 15 with a bead 16 to fit closely against the face of the reflector 5. In order to prevent noise, rattling, or injury to the reflectors where they meet, or the escape of light through the joint between the reflectors, I also preferably provide a cord or band of textile material 17, such as felt, plush, or velvet for instance, which rests in the recess or bead 16, and is retained thereby against displacement.

The light bulb 9 being out of the focus of the reflector, and the face of the reflector 10 directed toward the bulb 9 being convex, both tend to disseminate the light rays given 110

out from the bulb 9, so that there will be no region of sufficient intensity to have a blinding effect.

The light rays directed upwardly and forwardly from the bulb 8 and which without the insert reflector would be liable to interfere with the vision of others are received by the concave faces of reflector 10 and the tongue 11 thereof, and are either interrupted entirely or reflected downwardly upon the lower portion of the reflector 5. From reflector 5 these rays are again reflected together with other downwardly and rearwardly directed rays from the bulb 8 along paths to produce a wide flat fan or blade shaped pencil of rays directed upon the road in front of the vehicle, and which I have found to give the most satisfactory illuminating results. This type of supplemental reflector also affords sufficient diffused light or rays of less intensity at the opposite sides of the intense central blade of illumination so that trees, houses, and other objects at the sides of the road may be seen and possible obstructions avoided. This diffused light at the sides also materially assists in rounding curves in the road where the pencil of intense illumination temporarily does not fall upon the road. The blade of intense illumination is directed from the lower portion of the reflector, and at no point is high enough to materially interfere with other persons. The reflectors 10 may readily be inserted and applied to any reflector lights heretofore in use of the general type illustrated.

The apparatus herein illustrated and described is capable of considerable modification within the scope of the claims without departing from the principle of my invention.

What I claim is.

1. In combination with a reflector of the parabolic type having a source of light at substantially the focal point of said parabolic reflector, an insert reflector comprising two curved reflecting surfaces intersecting along a vertical plane at substantially the focal point of said parabolic reflector and having a marginal flange to closely fit the surface of said parabolic reflector and an interposed light excluding packing material between the adjacent faces of said parabolic reflector and said insert reflector, said insert reflector serving to divide the space within said parabolic reflector into an upper compartment and a lower compartment with said source of light in said lower compartment.

2. A search light comprising a reflector the lower half of which is of the parabolic

type, and the upper portion of which comprises two concave downwardly reflecting curved faces intersecting at a medial rib above the focal point of said parabolic section, and a source of light at substantially the focal point of said parabolic section, from which the upwardly and forwardly directed rays are intercepted by said rib and downwardly reflecting curved faces.

3. A search light comprising a reflector of the parabolic type, a light bulb at substantially the focal point of said reflector and a light bulb in the upper portion of said reflector, and a reflector interposed between said light bulbs and presenting a convex reflecting surface at each side of a vertical medial line toward the light bulb in the upper compartment, and a concave reflecting surface at each side of a medial vertical line toward the light bulb in the lower reflector compartment, united by a medial rib extending downwardly at its forward end and serving to intercept the upwardly directed and centrally forwardly directed rays from the light bulb in the lower reflector compartment.

4. In combination with a reflector of the parabolic type, having a source of light at substantially the focal point of said parabolic reflector, an insert reflector having two concave downwardly reflecting curved surfaces meeting in a middle rib from front to back of the reflector substantially above the focal point of said parabolic reflector, said insert reflector being located above said source of light and dividing the interior space of said parabolic reflector into an upper and lower compartment and intercepting the upwardly directed and centrally forwardly directed rays from said source of light and reflecting a portion thereof upon the lower half of said parabolic reflector to be thereby reflected out upon the road.

5. In combination with a reflector of the parabolic type having a source of light at substantially the focal point of said parabolic reflector, an insert reflector having two concave downwardly reflecting surfaces meeting in a middle rib from front to back above the source of light and dividing the interior space of said parabolic reflector into an upper compartment and a lower compartment, said insert reflector having supporting lugs at the extremities of its front edge and a point of engagement with the light socket at the rear of said parabolic reflector.

In testimony whereof I have affixed my signature.

HOWARD B. STAMM.
